[57] CLAIM

The ornamental design for a container for a type font disc, as shown and described.

DESCRIPTION

FIG. 1 is a perspective view of a container for a type font disc showing my new design;

FIG. 2 is an enlarged scale right side elevational view, the opposite side being a mirror image thereof;

FIG. 3 is a rear elevational view thereof;

FIG. 4 is a front elevational view thereof;

FIG. 5 is a top plan view thereof; and

FIG. 6 is a bottom plan view thereof.

FIG. 6
